UNITED STATES PATENT OFFICE.

JOHN SAXE, OF CARTAGO, COSTA RICA, CENTRAL AMERICA, ASSIGNOR OF ONE-HALF
TO HENRY GERRY PURDY, OF SAN JOSE, COSTA RICA, CENTRAL AMERICA.

COLLAPSIBLE TUBE.

Application filed July 2, 1925. Serial No. 41,024.

To all whom it may concern:

Be it known that I, JOHN SAXE, a citizen of the United States, residing at Cartago, Costa Rica, Central America, have invented 5 a new and useful Improvement in Collapsible Tubes, of which the following is a specification.

This invention relates to collapsible tubes for containing and dispensing viscous substances, and my improvement is particularly directed to devices of this kind such as are used with tooth paste, shaving paste, unguents, and the like.

One of the objects of my invention is to 15 provide a cap or closure device for collapsible tubes of such nature that the tube and cap can be fitted together and securely united by simply pressing them one against the other and can be disconnected by pulling 20 them apart, thereby avoiding the screwing and unscrewing operations involved by the use of screw caps.

The necessary security in the union that is made between cap and tube is provided by 25 giving globular form to the tube nozzle, like the male part of a snap fastener, and by giving complementary shell-like form to the cap, with slits in its wall, that it may resemble the female part of a snap fastener.

30 A further object of my invention is to equip the cap with means whereby it may be attachable to a shelf, wall or other object or surface to become a fixture having a definite location, so that the collapsible tube when fitted thereto by means of its nozzle occupies a particular predetermined position, where it is always at hand for removal and service.

In the daily use of tooth paste, shaving paste, etc. it is common to leave the tube un- 40 covered to save bothering about screwing on the cap, and often, too, the cap becomes lost, but when, after using the tube it is merely necessary to press its nozzle into a cap having a fixed location, thereby in the 45 one act putting the tube away and closing it, both orderliness and sanitation are served in one act, with a minimum of effort.

Other features and advantages of my invention will hereinafter appear.

50 In the drawing:

Figure 1 is an elevation of my improved closure means for collapsible tubes, shown as provided with attached means whereby it is secured to a fixed support in the form 55 of a wall.

Fig. 2 is a bottom plan view of said closure means.

Fig. 3 is a top plan view of a collapsible tube with the closure means removed.

Fig. 4 is an elevation of the closure means 60 having a modified form of support attaching means, said view showing a collapsible tube as pendent from the closure means, and Fig. 5 is a perspective view of the modification.

In said figures let 1 indicate a collapsible tube of well known character, except that its neck 2 is surmounted by a swelled or globular formation 3, like the male portion of a snap fastener. Also the cap 4 is provided 70 with a pendent annular portion or wall 5, that is globular in form and composed of spring-like material, said portion having the vertical slits 6, the mouth of said portion being smaller in diameter than the 75 major diameter of formation 3, so that the portion 5 may function like the female member of a snap fastener in effecting engagement and disengagement between the cap and tube.

80 By the means described the cap of a collapsible tube may be applied and removed respectively in the simple acts of pressing said elements together and pulling them apart, thus avoiding the greater labor required in screwing on and off according to present practice.

85 The advantage thus gained is especially desirable when the cap is held in a fixed position, so that the tube can be applied to its 90 closure means, and thus may be put away after use in a permanent and convenient location, while at the same time closing its nozzle opening.

95 Therefore, as a further feature of my invention, I provide the cap with attached means whereby it may be connected with a wall, shelf or other suitable support.

In Figure 1 the attached means take the form of a screw 7 which extends from the 100 cap and is provided with offset means 8 to provide a bracing effect and to permit finger grasp thereof to be had for driving the screw into a support, such as that indicated at 9.

105 Or, where the cap is to be secured to a shelf, such as may be of glass or material incapable of receiving a screw, then the means attached to the cap may include a clip such as that indicated at 10 in Figs. 4 and 5, 110

where it is shown as composed of folded wire or rod adapted to straddle and frictionally engage a shelf 11.

Variations within the spirit and scope of my invention are equally comprehended by the foregoing disclosure.

I claim:

As a new article of manufacture, a closure cap having snap fastener engagement with the nozzle of a collapsible tube, a holder integral with and extending substantially

right angularly from the axis of said cap, said holder being provided with means for securing it to a fixed support, and bracing means integral with and extending laterally from said holder, said bracing means being centrally arranged relatively to the cap and adapted to coact with the fixed support to resist the pressure applied in forcing the tube nozzle into said cap.

Executed this 20th day of June, 1925.

JOHN SAXE.
